H. G. BATTON

CLOTHESLINE

Filed Dec. 19, 1923

Fig. 1.

UNITED STATES PATENT OFFICE.

HENRY GRADY BATTON, OF SILSBEE, TEXAS.

CLOTHESLINE.

Application filed December 19, 1923. Serial No. 681,579.

To all whom it may concern:

Be it known that I, HENRY G. BATTON, a citizen of the United States, residing at Silsbee, in the county of Hardin and State of Texas, have invented new and useful Improvements in Clotheslines, of which the following is a specification.

This invention relates to laundry apparatus, particularly to clothes lines and has for its object the provision of a novel metallic clothes line provided with means for holding articles without the employment of clothes pins or any other auxiliary securing devices.

Another object is the provision of a clothes line of this character which is so constructed as to support twice as many articles as can be hung from an ordinary line, the device thus economizing in space and being very suitable for use in crowded districts where very little space is available for the purpose of drying clothes.

Still another object is the provision of a device of this character which consists of a plurality of links pivotally connected whereby the entire line may be folded into a small compact bundle.

With the above and other objects and advantages in view the invention consists in the details of construction to be herein-after more fully described and claimed and illustrated in the accompanying drawings, in which:

Figure 1 is an elevation of a portion of a clothes line constructed in accordance with my invention several links being disclosed,

Figure 2 is a detail perspective view of one link.

Referring more particularly to the drawings I have shown my line as comprising a plurality of similar links or lengths 10 each of which is formed from a single piece of wire of suitable gage, length and material formed at its ends with eyes or loops 11. The eyes of the successive links are interengaged as shown whereby all the links will be pivotally connected to be capable of folding into a small compact bundle which will be convenient in storage and transportation. The material may very well be galvanized

iron wire, as such is suitable for the purpose 50 inasmuch as it will not ordinarily corrode.

The essential feature of the present device is the provision of means for holding clothes or other articles to be dried. This means consists of a pair of clamping members 12 disposed at or near the center of each link at opposite sides thereof and soldered, brazed, welded or otherwise suitably secured thereto. Each of the clamps 12 is formed from a single length of wire of convenient length having its ends looped as shown at 13 and curved away from the link as is clearly shown.

It is of course apparent that the line is flexible as it is composed of a plurality of 65 sections pivotally connected and the use is of course obvious especially as the clamps provide adequate means for holding clothes or other articles to be dried. As the clamps are in duplicate on each link it is apparent 70 that twice the ordinary number of articles may be supported, a feature which makes the device particularly attractive for use in congested districts where space is scarce.

While I have shown and described the 75 preferred embodiment of the invention it is of course to be understood that I reserve the right to make such changes in the form, construction and arrangement of parts as will not depart from the spirit of the invention or the scope of the subjoined claim.

Having thus described my invention I claim:

A clothes line comprising a plurality of 85 links each formed from a single length of wire having its ends bent to define eyes, the eyes of the successive links being interengaged to constitute pivotal connections, and a pair of clamping members secured upon opposite sides of the intermediate portion 90 of each link, each clamping member consisting of a single length of wire having its intermediate portion secured to the link and having its ends formed with loops and curved away from the link. 95

In testimony whereof I affix my signature.

HENRY GRADY BATTON.
